UNITED STATES PATENT OFFICE

FREDERICK ROHLEDER, OF VAUX HALL, NEW JERSEY

LATHERING DEVICE

Application filed November 23, 1931. Serial No. 576,879.

This invention relates to improvements in massaging devices and more especially to a massaging device to be employed as a shaving accessory.

Usually, in preparing a beard for shaving, after the soap lather is applied, it is rubbed into the hair by hand. This not only makes a messy task of the rubbing in, but makes it necessary to wash and dry the hand used in applying the lather before grasping the razor for shaving purposes.

The primary purpose of the present invention is to provide a device to eliminate the rubbing in by hand of the lather, and one which will not alone apply the lather in a better way, but which will massage the skin while the lather is being applied.

Another object is to provide a device of this character, in which the rolling balls forming part of the same are arranged in rows positioned on the bias relatively to the axes about which the balls roll, whereby the balls in moving over the skin are relatively staggered and act to reach all parts of the skin over which the device is moved.

A still further object is to so mount the balls of the device that they are resiliently connected to the handle which permits the rows of balls to yield in action to resiliently press against the skin and conform to the uneven surfaces of the skin.

With the foregoing objects outlined and with other objects in view which will appear as the description proceeds, the invention consists in the novel features herein-after described in detail, illustrated in the accompanying drawing, and more particularly pointed out in the appended claim.

In the drawing,
40 Fig. 1 is a side elevation of my improved lathering device.

Fig. 2 is an end elevation of the same.

Fig. 3 is a bottom plan view of the device.

While the device may be made in a number 45 of ways, I prefer to construct it as follows.

A plurality of supporting elements formed of resilient wire are bent into shape so that each comprises a horizontal shaft portion 4 from which rises a plurality of arms 5.

50 These arms are rigidly connected at their

upper ends to a ferrule 6 which in turn is rigidly connected by any suitable means, such as a screw 7 to a handle knob 8. The outer arms at each end of the device are secured together by cross straps 9 which prevent these arms from moving away from one another.

On the shaft portion 4 of each of the supporting members, I arrange a series of balls 10, preferably formed of ceramic material 60 and adapted to rotate on the shaft.

For the purpose of keeping the balls of the different rows positioned in bias formation relatively to the shaft portions 4, the ends of these shaft portions are joined together by resilient connecting wires 11 which, as shown at 12 are looped about the shaft portions. As illustrated in Fig. 3, these connecting elements 11 are arranged at obtuse angles relatively to the shaft portions 4.

In operation, after the soap is applied to the beard, the operator grasps the handle 8 and then moves the balls back and forth over the skin. Obviously, the balls will act to work the lather into the beard, and to simultaneously massage the skin and it will do this in a much more effective manner than can be obtained by the lone use of the hand.

From the foregoing it is believed that the construction, operation and advantages of 80 the invention may be readily understood, and it is manifest that changes may be made in the details disclosed, without departing from the spirit of the invention, as expressed in the claim.

What I claim and desire to secure by Letters Patent is:

A lathering device comprising resilient supports, each support having a shaft portion from the ends of which arms project, a handle connected to the ends of said arms, all of said arms converging toward said handle, rows of balls rotatably mounted on said shaft portions, parallel connecting members joining said shaft portions and positioned at obtuse angles relatively to said shaft portions for maintaining said balls in rows arranged on the bias relatively to said shaft portions, and connecting elements arranged 90 95 100

above the balls and connecting the arms at each end of the device for maintaining said parallel connecting members in positions at obtuse angles relatively to said shaft
5 portions.

In testimony whereof, I hereto affix my signature.

FREDERICK ROHLEDER.
